UNITED STATES PATENT OFFICE.

OSCAR DURYEA AND LUCILE LE MAIRE, OF NEW YORK, N. Y.

LOCK FOR TELEPHONES.

Application filed October 6, 1923. Serial No. 667,014.

To all whom it may concern:

Be it known that we, OSCAR DURYEA and LUCILE LE MAIRE, both citizens of the United States, and residents of the city of New York, borough of Manhattan, in the county and State of New York, have invented a new and Improved Lock for Telephones, of which the following is a full, clear, and exact description.

10 The present invention relates to new and useful improvements in devices for locking telephones, and it pertains to a device particularly adapted for use in connection with telephones of the desk stand type.

15 It is one of the objects of the invention to provide an attachment for telephone stands, the use of which prevents movement of the telephone receiver supporting hook, and consequently preventing closing of the 20 telephone circuit for operation.

It is a further object of the invention to construct the device in such a manner that it is applicable to telephone stands of different types, thus rendering the device universal in connection with telephone stands.

It is a further object of the invention to construct the device in such a manner that it is readily attached or detached with respect to the telephone stand.

30 With the above and other objects in view, reference is had to the accompanying drawings, in which—

Figure 1 is a detail view in elevation showing the attachment secured to a telephone stand;

35 Fig. 2 is a detail elevational view partly in section, taken at right angles to Fig. 1, on the line 2—2 of said Fig. 1;

Fig. 3 is a perspective view of the attachment, the longer member thereof not being shown.

Referring more particularly to the drawings, the reference character 5 designates the telephone stand, and as is the customary practice the stand is formed at its upper end with an annular bead 6. The reference character 7 designates the receiver supporting hook common to telephone instruments of this type, and 8 designates the mouth-piece of the instrument.

The attachment comprises a band 9 adapted to encircle or embrace the telephone stand 5 with the upper edge 10 of the band 9 underlying and contacting with the annular bead 6 heretofore mentioned. The band 9 has an open side provided with lugs 11

through which passes a suitable bolt or screw 12 for securing the band to the telephone stand. Located above the lugs 11 are two lugs 13, the latter lugs being spaced with respect to the lugs 11. The lugs 13 are provided in their upper portion with openings 14, which although shown as rectangular in form, may be of any desired shape or contour, and immediately below the openings 14, the lugs 13 are provided with openings 15. The reference character 16 designates a rigid member preferably of rectangular form, such member 16 having a head portion 17 on one end and in its opposite end it is provided with an opening 18. The reference character 19 designates a lock, and 20 designates the shackle thereof, which is adapted to be received within the opening 18 of the rigid member 16 to prevent removal of the rigid member 16 as shown in Fig. 2.

The device operates in the following manner:

When the band 9 is secured in position upon the telephone stand, as shown in Figs. 1 and 2, the upper openings 14 in the lugs 13 will be in such position that the rigid member 16 when inserted thereinto will overlie the telephone receiver supporting hook 7 and prevent vertical movement thereof, and consequently prevent closing of the telephone circuit, it being understood that the upper edge 10 of the band engages the bead 6 and prevents movement of the band relative to the stand 5. If, now, the rigid member 16 be positioned as shown in Figs. 1 and 2, and the shackle 20 of the lock 19 attached thereto, operation of the telephone will be prevented.

In certain types of telephone stands the supporting hook 7 is downwardly bent to a greater degree than is shown in the present drawings, and in connection with telephone stands of such construction, the rigid member 16 would be inserted through the lower opening 15 in order that it may overlie the telephone receiver supporting hook and thus prevent operation thereof.

While in the present instance a padlock, such as 19, has been illustrated, it is obvious that any other type of locking device may be used in connection with the rigid member 16 without departing from the spirit of the invention since the particular type of lock is not important.

From the foregoing it is apparent that

the present invention provides means whereby a telephone may be locked against unauthorized use, and at the same time the locking means is simple in its construction, inexpensive to manufacture, and highly efficient in its operation to obtain the result desired.

What is claimed is:

- 10 1. A lock for telephones comprising a band adapted to encircle a telephone stand in proximity to the receiver supporting hook, a pair of spaced lugs projecting from said stand encircling band and adapted to receive the receiver supporting hook therebetween, said lugs having aligned perforations therein, a headed locking bolt removably mounted in two of said aligned perforations, and locking means carried by said locking bolt.
- 15 2. A lock for telephones comprising a band adapted to encircle a telephone stand, means for securing said band to the telephone stand with its upper edge in engagement with the bead formed near the upper
- 20 25 end of the stand to prevent upward movement of the band relative to the telephone

stand, a pair of spaced lugs carried by said band, said lugs having spaced and aligned openings, a rigid member adapted to pass through two of said aligned openings and have engagement with the receiver hook, and means for locking said rigid member against displacement relative to the aligned openings in which it is received.

3. In combination with a telephone stand 35 having an annular bead near its upper end and a receiver supporting hook, a band adapted to encircle said stand in engagement with said annular bead whereby movement of the band upwardly of the stand is 40 prevented, a plurality of oppositely disposed ears formed integrally with said band, two of said ears being adapted to receive the receiver supporting hook therebetween, means passing through two of said 45 ears for securing said band to the telephone stand, and means passing through other of said ears and adapted to overlie the receiver supporting hook.

OSCAR DURYEA.
LUCILE LE MAIRE.
